PHOTOGRAPHIC SLIDE BINDER

Julius Huisgen, New York, N. Y., assignor to E. Leitz, Inc., New York, N. Y., a corporation of New York

Application June 25, 1949, Serial No. 3,539

Term of patent 14 years

(Cl. D61—1)

To all whom it may concern:

Be it known that I, Julius Huisgen, a citizen of Germany, residing in the city, county and State of New York, have invented a new, original, and ornamental Design for a Photographic Slide Binder, of which the following is a specification, reference being had to the accompanying drawing, forming a part hereof.

In the drawing:

Figure 1 is a view, in perspective, of the photographic slide binder showing my new design.

Figure 2 is a rear elevational view of the same.

Figure 3 is an end view of the slide binder.

The essential features of my design for a photographic slide binder reside in the parts shown in

full lines, the broken lines shown in Figures 1 and 2 have been omitted from Figure 3 for convenience of illustration.

I claim:

The ornamental design for a photographic slide binder, substantially as shown and described.

JULIUS HUISGEN.
